UNITED STATES PATENT OFFICE.

WILLIAM C. STEVENS, OF AKRON, OHIO, ASSIGNOR TO PIERCE WRAPPING MACHINE COMPANY, OF CHICAGO, ILLINOIS, A CORPORATION OF ILLINOIS.

WRAPPING-MACHINE.

1,196,044.

Specification of Letters Patent. Patented Aug. 29, 1916.

Application filed August 18, 1912. Serial No. 715,745.

To all whom it may concern:

Be it known that I, WILLIAM C. STEVENS, a citizen of the United States, and a resident of the city of Akron, in the county of Summit and State of Ohio, have invented certain new and useful Improvements in Wrapping-Machines; and I do hereby declare that the following is a full, clear, and exact description of the same, reference being had to the accompanying drawings, and to the numbers of reference marked thereon, which form a part of this specification.

This invention relates more particularly to a machine for spirally wrapping or winding a covering strip, such as paper, about annular bodies, for example, automobile tires, and coiled wire and the like, or, of course, to afford a spirally wound wrapping about polished pipe, rods, or any other object capable of receiving such a wrapping. Heretofore, practically all, or a large part of such wrapping, has been done by hand, and, in consequence, the expense for such wrapping has been unnecessarily large, and the wrappings have not been applied with such uniformity as to present a pleasing appearance, nor sufficiently well so that the wrapping would remain long in place. Those articles so wrapped, have soon become exposed by the slipping of the wrapping material, thus presenting a very unsightly appearance, and, what is more serious, permitting injury to the contents of the package.

The object of this invention is to afford a wrapping machine adapted for operation at high speed, to wrap annular objects with substantial uniformity, and to apply a continuous spirally wound covering thereon.

It is also an object of the invention to afford an exceedingly simple and compact device for the purpose specified, having a large range of adjustment, to adapt the machine for wrapping annular bodies of different sizes, and in which the utmost facility for the insertion of the body to be wrapped, and the removal of the same from the machine after the wrapping, is attained.

It is also an object of the invention to provide means for positively supporting, and for rotating the body to be wrapped, and for adjusting said supporting and ro-

tating means relatively to each other and the wrapping mechanism.

It is an object of the invention also to afford an annular shuttle, having a reel of wrapping material mounted thereon, and means for rotating said shuttle through the eye of the annular body to be wrapped, while simultaneously rotating said annular body.

The invention embraces other important objects, as more fully hereinafter set forth.

The invention (in a preferred form) is illustrated in the drawings, and hereinafter more fully described.

In the drawings: Figure 1 is a side elevation of a device embodying my invention, showing the annular body to be wrapped, in dotted lines. Fig. 2 is a central, transverse section thereof, with parts in elevation. Fig. 3 is an enlarged, sectional view, taken on line 3—3 of Fig. 2, and with the belt pulleys shown in elevation. Fig. 4 is an enlarged face view of the annular shuttle and the mechanisms carried thereon. Fig. 5 is an edge view of the same. Fig. 6 is a section on line 6—6 of Fig. 4. Fig. 7 is a fragmentary detail, partly in section, of a part of the shuttle. Fig. 8 is an elevation of shuttle locking means. Fig. 9 is a delivery end elevation of the folding nozzle. Fig. 10 is a front face view thereof. Fig. 11 is an enlarged face view of the reel carrier. Fig. 12 is an enlarged, sectional view of the front adjustable guide pulley. Fig. 13 is a sectional view, with parts in elevation, of the upper or rear guide and driving pulley for the shuttle.

As shown in the drawings: 1, indicates a relatively low base or table, supported upon a suitable frame or legs 2, and having a central longitudinal slot therethrough. Journaled transversely of said table on the top thereof, is a driving shaft 3, having at the outer end thereof, a tight and a loose belt pulley 4 and 5, respectively, adapting the shaft to be driven from any suitable source of power. Mounted upon said table at one side of said central slot, is an upright, crescent shaped frame 6, which, as shown, is rigidly bolted to said table with the arms of the crescent directed upwardly and outwardly, or forwardly, as shown in Fig. 1.

Rigidly secured on said shaft 3, is a belt pulley 7, having a peripheral flange 8, projecting circumferentially on each face thereof, affording a grooved periphery for the belt 9. Journalized longitudinally of the table on each side of said belt pulley 7, in bearings 10 and 11, are shafts 12 and 13, having eccentric bearing portions, each of which extends through a sleeve 14, provided with upwardly directed front and rear bracket arms 15 and 16, as shown in Fig. 1, at the upper ends of each pair of which is journalized a shaft 17, having a grooved roller 18, rigidly secured thereon. The rear end of each of said shafts 17, is provided with a sprocket wheel 19, about which is trained a sprocket chain 20, which also is trained about a sprocket wheel 21, journalized on the shaft 12, and integrally, or otherwise rigidly connected with the worm gear 22, also rotatably journalized on said shaft and in mesh with a worm 23, on the shaft 3, so that the rotation of said shaft 3, by means of its tight belt pulley, acts through the medium of said worm and worm gear and sprocket wheels and chain, to rotate the grooved feed or advancing rollers 18. Means are provided for adjusting said feed or advancing rolls relatively to each other. For this purpose, as shown, a downwardly directed arm 24, is provided on each of said sleeves 14, and carried on the lower end of each is a nut 25, through which extends a screw shaft 26, pivotally mounted in a suitable bearing 27, therefor, secured upon the table 1, rotation of one of said screw shafts acting on the nut 25, to swing the corresponding advancing or feed roll outwardly or inwardly, dependent upon the direction of rotation, thus enabling either or both of said advancing and feed rolls to be adjusted to the most efficient position for supporting and rotating or advancing the object to be wrapped. Outward adjustment of said feed rolls obviously permits the supported object to be supported somewhat lower in the machine, while inward adjustment of the feed rolls supports said articles higher in the machine. Rotation of the shafts 12 and 13, because of the eccentric mounting thereof, serves also to vary the tension on the corresponding sprocket chain 20. Mounted on said grooved driving pulley 7, with its flat periphery fitting in the groove in the periphery of said driving pulley, is the annular shuttle 28, which is thus mounted transversely of the tire or other body to be wrapped. Extending through the forward arm of the crescent frame 6, at its extremity, is a shaft 29, provided on the inner side of the frame with a collar 30, to bear against the face of the frame and at its outer end provided with a nut 31, or other means for rigidly securing the same from movement.

in the frame. Eccentrically connected with said shaft 29, at its inner end, or that opposite the nut 31, is a wrist pin 32, on which is journalized a peripherally flanged pulley 33, which may be constructed in any suitable manner, or, as shown in Fig. 12, laid up in part of sections of friction paper or other suitable material 34. Said flanged pulley is held in place on the wrist pin 32, by means of suitable nuts or other releasable means 35. The other or rear arm of said crescent frame 6, at its extremity, is longitudinally slotted, as shown in Fig. 13, and extending through the slot is a bolt 36, provided with a head 37, which bears against one side of said arm, while suitable nuts 38, as shown in Fig. 13, engage the other side thereof to clamp said bolt rigidly in adjusted position. A stud shaft 39, integral with said bolt, projects outwardly from the head thereof, and journalized on said stud shaft is a grooved belt pulley 40. Said grooved pulleys 34 and 40, receive the periphery of the annular shuttle 28, in the grooved faces thereof, while said shuttle is supported on the grooved driving pulley 7, thus engaging said shuttle at three points, at substantially equal distances apart, and permitting the shuttle to rotate freely therewith and therebetween. A belt 9, trained about the grooved driving pulley 7, and the grooved pulley 40, also engages the periphery of the shuttle 28, for the entire distance between the pulley 7, and said pulley 40, thereby acting to rotate said shuttle.

A hinged section 41, is provided in said shuttle to permit the opening thereof for the insertion or removal of the article to be wrapped. As shown, said hinged section is pivotally engaged at one end on the end of the shuttle member 28, by means of a pin 42, and at the other end is provided with a projection 43 on both sides thereof, adapted to receive the web 44, of the shuttle therebetween. A pin 45, extends transversely through said projections, and is adapted to seat in an inclined notch 46, as shown in Figs. 4, 6, and 7, in the other end of said shuttle member, thus insuring a true periphery for the shuttle under all conditions when the hinged section is closed, as shown in Figs. 4 and 7. Means are provided for locking said hinged section in closed position. For this purpose, as shown, a notch in the shuttle 28, indicated at X, in Fig. 7, is provided at the inner periphery thereof, and pivotally supported by means of a bolt 47, extending radially from the inner side into said hinged section 41, of the shuttle is a swinging detent 48, having a finger 49, adapted to engage in said notch. The elongated tail 50, of said detent extends oppositely from said finger around the inner periphery of said hinged segment, and pivotally mounted thereon is a lever 51, one end

52, thereof, engaging in a suitable notch or recess in said hinged section. As shown, a spring 53, engages the free end of said lever 51, and acts to hold the same normally in locking position, as shown in Fig. 4. When it is desired to release the hinged section, the tail of the lever is pressed downwardly to the tail 50, of the detent, thus releasing the locking end of the lever, whereupon the lever 10 may be swung laterally, carrying the finger 49, thereon out of the notch X, and permitting the shuttle to be opened. Mounted on the face of said shuttle at the side opposite the crescent frame 6, and diametrically 15 opposite the hinged section of the shuttle, is an inwardly and laterally inclining stud shaft 54, and provided, as shown, with a face plate or collar 55, rigidly secured thereon. Said stud shaft extends upwardly 20 through the collar or hub 56, of said collar or face plate, as shown in Figs. 4 and 11. Said hub is of a diameter to fit in the bore or core in a paper reel 57, having the paper (or other wrapping material) 58, wound 25 thereon, as shown in Figs. 1, 2, 4, 5 and 11, and secured on the upper end of said hub, and extending peripherally, but eccentrically around the same, are springs 59, each at its free end provided with an outwardly 30 extending and slightly inwardly inclined projection 60, adapted when the reel of wrapping material is pressed thereover, to spring inwardly to permit the reel to receive the hub therethrough with said springs engaging 35 over the outer face of the reel to hold the same from displacement, and afford tension. Mounted upon a bracket 61, pivotally and obliquely secured upon the face of said reel, is an edge turning or folding device 62, 40 comprising a sheet or plate of metal bent to afford a tapering nozzle 63, comprising an inner and relatively narrow fold, an outer wider fold, and a lip 64, integral with the outer fold, and turned over the inner. The 45 opposite end of said nozzle is wider and flaring to receive the paper and other material therein, as shown in Figs. 4 and 5. Said nozzle is secured on the bracket 61, in any suitable manner, with the tapered end 50 thereof directed outwardly and adjacent said tapered end, and set in the face of the shuttle, is a stud shaft 65, that is approximately parallel with the stud shaft 54. Journaled on said stud shaft, is a roller 66, 55 or, if preferred, the stud shaft may be provided merely with a rounded or convex face over which the paper, or other wrapping material, may be drawn to set the fold therein and to direct the strip suitably to 60 the article to be wrapped.

Mounted upon the table at the rear of the shuttle, and rigidly secured in a bracket 67, is a standard 68, and adjustably secured on said standard in any suitable manner, is a 65 yoke 69, having journaled between its arms

an upright roller 70, as shown in Fig. 1, and against which the top of the tire, or other annular body to be wrapped, rests, and travels during the wrapping operation.

The operation is as follows: The machine 70 is first adjusted to the size of the annular bodies to be wrapped, and this is accomplished by adjusting the advancing or feeding rollers 18, inwardly or outwardly toward the shuttle by means of the screw 75 shafts 26. The yoke 69, carrying the roller 70, is then adjusted upwardly or downwardly on the standard, and outwardly or inwardly, as required, to properly support the top of the annular body, as indicated in 80 dotted lines in Fig. 1. If not previously satisfactorily adjusted, the grooved rollers 33 and 40, are adjusted to bear upon the periphery of the shuttle, and together with the grooved pulley 7, afford three points of 85 contact and support for the shuttle, between which the same is rotated, said shuttle, of course, having frictional engagement with the grooved driving pulley 7, the grooved roller 40, and one run of the belt between 90 the same. Having so adjusted the machine, the shuttle is opened by means of the lever 51, which permits the detent lever 50, to be swung to release the finger 49, thereof from 95 its seat or notch X, in the shuttle, thus permitting the hinged section of the shuttle to be swung outwardly and admitting of insertion of the tire, coil of wire, or other annular object, into the shuttle, so that each 100 may rotate through the eye of the other. The driving belt now being shifted to the tight pulley, the shuttle is rotated at a relatively high rate of speed, while the tire is rotated by means of the advancing rolls 18, 105 at a sufficient rate to give the desired lead for the material wound upon the tire or coil, while the paper or other wrapping material, is drawn from the reel through the folding nozzle 62, around the guide arm or roll 66, and thence, by the rotation of the 110 shuttle, is wound about the tire. The operation continues until the annular body is fully wound or covered, the driving belt is then shifted to the loose pulley, the machine stopping almost instantly, the shuttle 115 again opened, and the annular body removed and another inserted, whereupon the operation is repeated. When it is desired to replenish or to renew the paper reel, the extended ends 60, of the retaining springs 120 on the hub 56, are pressed inwardly, thus permitting the core of the reel to be removed and another reel or roll of paper to be inserted thereon.

Details of the construction may, of course, be varied through a wide range. I have, however, shown and described but a preferred form of my invention, although numerous details of construction and operation will readily suggest themselves. I 125

therefore do not purpose limiting the patent granted on this application, otherwise than necessitated by the prior art.

I claim—

- 5 1. A bed or table, a shaft journaled thereon having a tight and a loose pulley, a grooved supporting and driving wheel rigidly secured on the shaft and about the middle of the table, a yoked standard secured on said bed, a grooved pulley journaled on each arm thereof near its extremity and above the grooved driving wheel, a belt trained about the grooved driving wheel and one of said pulleys, an annular shuttle 10 supported on and between the grooved driving wheel and grooved pulley and bearing against one run of the belt, grooved feed rollers journaled at each side of the shuttle and at a right angle with the axis thereof to support the annular body to be wrapped, connections for driving the same from said shaft at a less rate of speed than the rotation of the shuttle, a standard on said bed, and a roller adjustably supported thereon and 15 adapted to support the top of the annular body when the machine is in operation.
- 20 2. In a wrapping machine of the class described an annular shuttle, grooved pulleys each engaging and acting to support said shuttle in upright position at more than two points, a belt trained about certain of said pulleys, one run thereof bearing against the shuttle to drive the same, one of said grooved pulleys acting to hold the shuttle against the belt, and independently adjustable swingingly mounted rotatable means for supporting an annular shaped article in position to be wrapped engaged through the eye of said shuttle, said means movable radially of 25 the article for adjustment of the article.
- 30 3. In a device of the class described a rotatable shuttle, paper carrying means thereon, rotatable means adapted to support said shuttle at more than two points, a belt 35 trained about two of said rotatable means and contacting a portion of the periphery of said shuttle, means driving one of said rotatable means to rotate the shuttle, and swingingly mounted mechanisms to support the article in position to be wrapped, adjustable radially of said article to shift the same.
- 45 4. A device of the class described comprising a main driving shaft, an annular upright shuttle driven thereby, shafts extending transversely of the main shaft, one at each side of the shuttle, an outwardly directed yoke journaled eccentrically on each of said shafts, a grooved pulley journaled 50 at the upper end of each yoke opposite the eye of the shuttle, worms on the main driving shaft, a worm gear journaled on each of said transverse shafts intermeshing with said worms on the main shaft, driving connections between the worm gears and said 55 grooved pulleys, and screw shafts, one at each side of the machine and engaging the respective yokes and acting to swing their grooved pulleys inwardly or outwardly to vary the adjustments of the machine as to 60 the size of the article to be wrapped.
- 65 5. A machine of the class described embracing an annular shuttle, a grooved driving wheel and grooved pulleys engaging the periphery of said shuttle therebetween at substantially equal distances apart, a belt trained around the driving wheel and one of said pulleys and bearing against the periphery of the shuttle to drive the same, means driving the driving wheel, grooved supporting rolls for the article to be wrapped adjustably supported at each side of the shuttle substantially opposite the eye thereof, means driving the same at a less rate of speed than the shuttle, and an adjustable guide rail for supporting the top of the body to be wrapped.
- 75 6. A wrapping machine comprising a rotatable shuttle, means carrying a supply of wrapping material thereon, mechanism associated with the shuttle to direct the wrapping material to the article wrapped, a plurality of grooved rollers affording a support for said shuttle, a belt trained about a part of said grooved rollers and a portion of the periphery of said shuttle whereby said shuttle may be driven from said rollers, and independently adjustable swingingly mounted mechanisms to support an article in position for wrapping.
- 80 7. In a device of the class described a frame, a shuttle rotatably mounted in vertical position therein, means supporting and rotating an article to be wrapped in vertical position engaged through the eye of said shuttle, said means swingingly adjustable in a vertical plane to raise and lower said article to a proper wrapping position.
- 85 8. In a device of the class described an annular shuttle, paper carrying means thereon, rotatable means contacting said shuttle on the periphery thereof substantially equidistant therearound to support the same, driving connections for one of said means, a belt trained around said last mentioned means and one other thereof, and contacting a portion of the periphery of the shuttle to rotate the same, swingingly mounted independently adjustable rollers adapted to support an article engaged through the eye of said shuttle, and driving connections for said rollers whereby the same may be operated simultaneously with movement of said shuttle.
- 90 9. In a device of the class described an annular shuttle, paper carrying means thereon, mechanism supporting said shuttle at a plurality of points substantially equi-distant around the periphery thereof, means trained around certain of said first mentioned means to drive said shuttle by contact therewith,
- 95 100 105 110 115 120 125 130

rollers adapted to support an article to be wrapped, means driving said rollers simultaneously with said shuttle, and a pivotal mounting one for each of said rollers where-
5 by the same may be adjusted to or from the shuttle to properly position articles of different size through the eye of said shuttle.

10. In a machine for the helical placement of a strip of continuous material on an annular object, means to support and revolve said object while permitting the vertical adjustment of the same comprising a frame, a pair of pivots on said frame, arms on said pivots capable of being swung in a vertical plane, a 5 roller on the free end of each of said arms arranged to support said object, means to transmit motion to one of said rollers for revolving said object, and a shuttle revolving about said object during its revolution 0 in a vertical plane, said shuttle provided with means for helically placing a continuous strip of material on said object.

11. A device for helically placing a strip of material about an annular object embodying as an element thereof, means to support and revolve said object in a vertical plane, said means consisting of a frame, a pair of pivots thereon, a freely-swinging arm on each of said pivots, a rotatable roller capable 5 of supporting said object pivotally mounted on the free ends of each of said arms, means for transmitting motion to one of said rollers, said arms when oscillated in a vertical plane capable of raising or lowering the 10 object, means to lock said arms in a pre-determined position, and a shuttle revolving about said object in a plane at right angles thereto and arranged to wind a strip of material helically about said object during its revolution.

12. A device for helically placing a strip of material about an annular object embodying as an element thereof, means to support and revolve said object in a vertical plane, 5 said means consisting of a frame, a pair of pivots thereon, a freely-swinging arm on each of said pivots, a rotatable roller capable of supporting said object pivotally mounted on the free ends of each of said arms, means 10 for transmitting motion to one of said rollers, said arms when oscillated in a vertical plane capable of raising or lowering the object, means to lock said arms in a pre-determined position, and a shuttle revolving 15 about said object in a fixed plane and arranged to wind a strip of material helically about said object during its revolution, and means supporting the upper portion of said object during its revolution.

13. In a wrapping machine of the class 60 described a rotatable power driven shuttle disposed and rotating in a vertical plane, swingingly mounted rollers adapted to support an article vertically in wrapping position, a drive shaft, driving connections between said rollers and said drive shaft whereby the article to be wrapped may be rotated by said rollers, and eccentric mechanism on which said swingingly mounted rollers are supported forming a part of said 65 driving connections to afford a take-up adjustment for said connections.

14. In a wrapping machine of the class described a vertically disposed rotatable annular shuttle, a crescent shaped support in 75 which the same is mounted, mechanisms adapted to support an article to be wrapped in vertical position engaged through the eye of said shuttle, means for adjusting said mechanisms toward and away from one another independently of each other, and in a vertical plane, a driving shaft, sprockets adapted to be driven therefrom, driving connections between said sprockets and said supporting mechanisms, and mechanism eccentrically supporting said sprockets with respect to said supporting mechanisms to 80 permit a take-up adjustment of said driving connections.

15. In a wrapping machine of the class described a shuttle rotatable in a vertical plane, swingingly mounted rotatable mechanisms for supporting an article to be wrapped in a vertical position, driving connections for 90 said mechanisms, and an eccentric mounting 95 for said mechanisms to permit a take-up adjustment of said driving connections.

16. In a machine of the class described the combination with a supporting frame, a pair of adjustable pivots thereon, each of which 100 embodies a rotatable shaft, an arm journaled on each shaft, rollers carried by the free ends of said arms, said rollers arranged to support a revolute and annular object in a vertical plane, said arms when oscillated adapted to 105 change the vertical position of said object, means to hold said arms in an adjusted position, and a shuttle carrying a continuous strip of material adapted to wind said strip helically on said annular object during its 110 revolution.

In testimony whereof I have hereunto subscribed my name in the presence of two subscribing witnesses.

WILLIAM C. STEVENS.
